UNITED STATES PATENT OFFICE.

FRANK H. JOHNSTON, OF CHICAGO, ILLINOIS, ASSIGNOR, BY MESNE ASSIGNMENTS, TO ACME CARD SYSTEM COMPANY, OF CHICAGO, ILLINOIS, A CORPORATION OF ILLINOIS.

REVERSIBLE CARD-INDEX HOLDER.

Application filed November 19, 1919, Serial No. 339,251. Renewed July 23, 1925.

To all whom it may concern:

Be it known that I, FRANK H. JOHNSTON, a citizen of the United States, residing in the city of Chicago, county of Cook, and 5 State of Illinois, have invented certain new and useful Improvements in Reversible Card-Index Holders, of which the following is a specification.

My invention relates to improvements in 10 reversible card index holders and refers more particularly to holders adapted for use in file cabinets or the like.

It has among its salient objects to provide a holder which is held in the drawer of a 15 cabinet; to provide a holder with index cards mounted upon both sides and adapted to be reversed so that entries may be made on the cards on either side; to provide a reversible card index holder which may be reversed 20 when the drawer is withdrawn from the cabinet and is hinged in either a vertical or horizontal plane so that when the holder is reversed it will lie in identically the same position in the drawer, no matter which side 25 is being used; to provide a reversible card index holder which has the drawer as a support when entries are being made on the cards on either side of the holder.

There are numerous ways in which the 30 holder may be reversed making it possible to use twice the number of cards upon the holders as are generally available on holders in card index cabinets. The first and most obvious being simply to lay the reversible 35 holder in the drawer and remove it to reverse it. This is rather awkward in operation and has the added disadvantage that holders may be removed and misplaced, and for that reason I suggest the following modifications.

In the drawings:

Fig. 1 is the reversible holder and drawer showing stud and groove reversing device.

Fig. 2 is a sectional edge view of assembly 45 shown in Fig. 1.

Fig. 3 is a sectional view of the end of the drawer shown in Fig. 1, with parts broken away.

Fig. 4 is a fragmentary detail of top of 50 the holder.

Fig. 5 is a holder with vertical hinges.

Fig. 6 is an edge view of side reversing hinge arrangement, shown in Fig. 5. Figs.

5 and 6 are modifications of holder in Fig. 1.

Fig. 7 is a fragmentary detail of the side 55 of the holder shown in Fig. 8.

Fig. 8 is an edge view of top pivoting rod or hinge; a second modification of the reversible holder.

Fig. 9 is an end view of the end revolving 60 hinges; a third modification of the reversible holder.

Referring in detail to the drawings, there are four means shown for reversing the card holder 1 in the drawer 2. In Figs. 1, 2 and 65 3, the slotted end pieces 3 in the drawer are engaged by studs 4 on the holder sliding therein. Figs. 5 and 6 show the side hinges 5 pivoted at 6 to the drawer and at 7 to the holder, thus allowing the holder to be reversed, end for end, in the drawer. It will be noticed in Fig. 6 that the cards 8 on the underside of the holder lie in a reversed position so that they will be properly arranged when the holder is reversed.

In Fig. 9, the hinges 9 are placed at the top and bottom of the holder (the bottom end only is shown as the top is identical with it) and are pivoted at the center 10 to the drawer and at 11 to the holder. With this arrangement, the holder is reversed, edge for edge, as in combination shown in 70 Fig. 1. The method shown in Fig. 8 has the holder pivoted at 12. When the drawer is open, the front end of the holder may 80 be lifted and turned back and entries made on the cards arranged in reverse order.

The card holders are of the usual design having lateral channels 13 which assist in supporting the cards. The end pieces 3 of 90 the drawers are high enough to allow clearance between the cabinet (not shown) and the cards when the drawers are slid out and in. The runners 14 are fixed to the bottom of the drawers and make the operation of the 95 drawers easier.

It has been the usual practice when using a card index cabinet to have cards mounted only upon one side of the holder in the drawer. With my invention, both sides of 100 the holder can be used for cards and with either side up the holder will be supported so that there will be a firm writing back for making entries upon the cards.

It is not my intention to restrict myself to 105 these means of reversing the holders, but I

have here set out some of the possible ways of carrying out my invention and I will specify more particularly in the claims.

I claim as my invention:

- 5 1. In a reversible card index holder, the combination with a slidable drawer having elongated slots in opposite end portions thereof, of a reversible card index holder adapted to be carried by said drawer and
- 10 10 movable therewith, studs projecting from said holder and entering said slots in the ends of the drawer, said holder being shiftable bodily relative to said drawer by a movement of the studs in said slots to permit the holder to be reversed.
- 15 2. In a reversible card index holder, the combination with a sliding drawer, the end portions of said drawer having elongated slots therein disposed in substantially the
- 20 20 same horizontal plane, a reversible card in-

dex holder carried by said drawer and movable therewith, studs disposed near one longitudinal edge of said card holder at each end thereof, said studs being adapted to enter the slots in the end portions of said drawer and slideable therein relative to said end portions to permit the holder to be moved relative to the drawer to reverse the exposed side thereof.

3. In an index holder, the combination 30 with a sliding drawer, of a reversible card index holder carried by said drawer and movable therewith, means connecting said holder with said drawer, said means permitting a sliding bodily movement of the holder relative to the drawer to permit the exposed portion of said holder to be reversed, substantially as described.

FRANK H. JOHNSTON.
